CLAIM

We claim the ornamental design for an information handling system, as shown and described.

DESCRIPTION

FIG. 1 is a front perspective view of the information handling system comprising the present invention; FIG. 2 is a front elevation view thereof; FIG. 3 is a rear elevation view thereof; FIG. 4 is a right side view thereof; FIG. 5 is a left side view thereof; FIG. 6 is a top view thereof; and FIG. 7 is a bottom view thereof; FIG. 8 is a bottom perspective view thereof; and, FIG. 9 is a front perspective view thereof in an open position.

Broken lines shown in the drawings illustrate portions of the information handling system and form no part of the claimed design.

The rectangular speaker grills shown in FIG. 9 form part of the claimed design as shown.

1 Claim, 6 Drawing Sheets
